UNITED STATES PATENT OFFICE.

WILLIAM EDWARD GORDON, OF WINNIPEG, MANITOBA, CANADA.

SPRING WINDING OR STRESSING MECHANISM FOR TALKING-MACHINES.

1,391,315.

Specification of Letters Patent. Patented Sept. 20, 1921.

Application filed November 11, 1919, Serial No. 337,232. Renewed August 15, 1921. Serial No. 492,587.

To all whom it may concern:

Be it known that I, WILLIAM EDWARD GORDON, of the city of Winnipeg, in the Province of Manitoba, Canada, have invented certain new and useful Improvements in Spring Winding or Stressing Mechanism for Talking-Machines, of which the following is the specification.

The invention relates to improvements in talking machines and particularly to means for driving the disk table and the principal object of the invention is to provide a driving motor embodying a helical or spiral spring as a source of power and which is connected by suitable gearing to the turntable spindle and is arranged such that when the spring is extended it will operate the spindle to drive the table.

A further object is to provide a hand lever by which the spring can be fully extended in one pull of the lever if desired, and arranged also such that the lever can be ratcheted step by step should the pull prove excessive such as for a child.

A further object of the invention is to provide a hand lever having a back and forward movement and connected with the motor of the talking machine and designed to energize the motor in the forward pulling of the lever.

A still further object is to associate with the lever and the turntable a brake mechanism adapted to stop the turntable when engaged by the lever.

A still further object is to provide a cheap, durable and efficient motor of the above kind and to arrange the parts such that they can be readily installed and assembled.

With the above more important objects in view the invention consists essentially in the arrangement and construction of parts hereinafter more particularly described and later pointed out in the appended claims, reference being had to the accompanying drawings in which:—

Figure 1 is a side view of a talking machine with the side broken away to expose interior parts.

Fig. 2 is a vertical sectional view at 2—2' Fig. 1 through the upper part of the machine.

Fig. 3 is a horizontal sectional view at 3—3' Fig. 2 and looking downwardly.

Fig. 4 is a vertical sectional view at 4—4' Fig. 3 and looking to the right.

Fig. 5 is an enlarged vertical sectional view at 5—5' Fig. 2 and looking toward the ratchet wheel.

Fig. 6 is a vertical sectional view through 60 the ratchet wheel and adjacent chain wheel.

Fig. 7 is a plan view of the brake lever and associated parts.

Fig. 8 is an enlarged side view of the upper end of the hand lever. 65

Fig. 9 is an enlarged front view of the upper end of the hand lever.

In the drawings like characters of reference indicate corresponding parts in the several figures. 70

1 represents the casing of a talking machine provided with the usual hinged top 2 and fitted with spaced cross partitions 3 and 3' which divide the cabinet into an upper compartment 4, a lower compartment 5 and 75 an intermediate horn compartment 5'. Centrally and to the underside of the partition 3 I secure permanently as by screwing a metallic base plate 6 which carries a pair of downwardly extending front hangers 7 and 80 8 and a pair of rear opposing downwardly extending hangers 9 and 10 which provide bearings for parts later disclosed.

11 represents a vertical spindle extending upwardly through the table and having the 85 lower end mounted in a suitable bearing provided at the lower end of the hanger 10. The upper end of the spindle carries a turntable 12 which turns with the spindle and receives and supports the record A in the 90 ordinary way. The lower end of the spindle is provided with a worm 13 which is in mesh with a worm wheel 14 mounted on a countershaft 15 carried by the hangers 7 and 8. The shaft 15 is fitted also with a 95 chain wheel 16 connected by a chain 17 or such like to a chain wheel 18 located on one end of a driving shaft 19 which is carried by suitable brackets 20 and 21 secured permanently to the back of the casing 1. 100

22 is a vertically disposed helical or spiral spring located in the rear right hand corner of the casing and within the lower compartment thereof, the lower end of the spring being permanently secured in any suitable 105 manner to the bottom of the casing.

23 is a chain permanently secured at 24 to the upper end of the spring and passing upwardly over a chain wheel 25 rotatably mounted on the end of the shaft 19 and then 110 connected at 26 to a hand lever 27. The lower end of the hand lever is pivotally

fastened at 28 to the bottom of the casing and the upper end extends through suitable forwardly extending slots 29 located in the partitions 3 and 3'. The arrangement of 5 the latter parts is such that the spring is collapsed when the lever is in its rearmost position at the back end of the slots and is fully extended as shown in dotted outline when the lever is at the front end of the 10 slots (see Fig. 1).

The chain wheel 25 is held against end movement on the shaft by a stationary collar 30 secured to the shaft and a ratchet wheel 31 keyed to the shaft and it carries a 15 spring pressed ratchet or pawl 32 operating on the ratchet wheel, the arrangement being such that when the lever is pulled ahead the ratchet escapes over the teeth.

Consequently after the lever has been 20 pulled forwardly the ratchet engaging the teeth will cause the shaft 19 to turn under the pulling action of the chain 23 as effected by the extended spring.

33 is a fly ball governor of the ordinary 25 form suitably carried by a shaft 34 mounted in the rear brackets 9 and 10, said shaft being provided with a worm 35 engaging a worm wheel 36 fastened to the spindle 11. The governor however forms no part of this 30 invention and is not herein further described.

In order to automatically stop the turntable when the lever has been pulled backwardly toward the rear end of the slot by the action of the spring, I have provided a 35 brake lever 38 pivotally mounted on a pin 38' carried by the partition 3. One end of the said lever crosses the rear end of the upper slot 29 while the other end is located to the rear of the table 12 and is fitted with 40 a friction shoe 39 such as leather adapted to engage the periphery of the table. A light coiled spring 40 is supplied to hold the shoe normally away from the turntable. Obviously as the lever 27 travels backwardly in 45 the upper slot and is approaching the rearmost end it will strike the adjacent end of the lever 37 and in carrying it back will force the other end toward the table 12 so that when the hand lever is fully back the brake lever has acted to stop the table rotating.

In order that there may be no difficulty in pulling the hand lever forwardly, such as where a child may be operating the machine, 55 I have provided the hand lever with a ratchet appliance which allows it to be worked ahead easily in a step by step movement. The ratchet appliance comprises a short auxiliary lever 41 pivotally connected 60 at 42 to an extension arm 43 hinged at 44 to the main lever, the hinge being arranged to allow the arm and short lever to swing in toward the turntable a limited distance where it is stopped by a lug 45 formed at 65 the hinge. The short lever is stopped in the

vertical position by a catch 46 located above the pivot 42 and arranged such that one can pull the main lever bodily once the short lever has engaged the catch. To the lower end of the short lever I connect pivotally at 70 47 a dog or pawl 48 which extends rearwardly and operates over a ratchet bar 49 permanently secured to the cross partition 3 immediately to the outer side of the upper slot 29. 75

When one wishes to operate this machine he places the record on the table in the ordinary way and then grasps the upper end of the short lever and pulls it ahead until it strikes the stop 46. If the party operating 80 the machine is strong enough to pull the main lever fully ahead in one movement against the action of the spring he continues pulling on the lever 41 after it has engaged the stop and the action carries the main 85 lever ahead to the front end of the slot, such movement fully extending the spring. Once the spring is extended there is sufficient power developed to play the entire record. If a small record is used it is not necessary 90 to draw the lever all the way forward and with a little practice one can determine the distance which it is necessary to draw the lever ahead, depending on the length of the record which is to be played. 95

If desired indicators can be placed on the side of the slot in a location as shown at 37 to show just how far the lever should be pulled ahead for the various lengths of records. 100

Where one is not strong enough to conveniently pull the main lever ahead in one stroke as just described he or she can ratchet the main lever ahead in a step by step movement, this being accomplished by swinging 105 the short lever alternately backwardly and forwardly. As the short lever moves in this way the dog 48 operates on the ratchet bar 49 to effect the forward movement of the main lever a few teeth displacement each 110 swing of the short lever. In this connection it will be observed that the ratchet wheel 31 and the pawl 32 act to hold the spring tension each time the main lever is advanced.

When the main lever has been advanced 115 as far as desired either by a straight forward pull or by a ratcheting action the dog 48 is thrown up against the catch 46 to permit the main lever to go back under the action of the spring.

When one desires to close the cover of the casing he swings the auxiliary lever inwardly toward the record as shown in Fig. 2.

What I claim as my invention is:—

1. In a talking machine, the combination 125 with the turntable spindle, of a helical spring having one end fast, a pivoted lever, a flexible connection between the lever and the other end of the spring, a wheel over which the connection runs, a shaft rotatably 130

carrying the wheel, means for coupling the wheel to the shaft when rotating in one direction and a driving connection between the shaft and the spindle.

- 5 2. In talking machine, the combination with the turntable spindle, of a helical spring having one end fast, a pivoted lever, a chain connecting the lever with the other end of the spring, a suitably mounted driving shaft, a chain wheel rotatably mounted on the shaft and carrying the chain, a ratchet and ratchet wheel for coupling the chain wheel to the shaft when rotated in one direction and a driving connection between 10 the shaft and the spindle.
- 15 3. In a talking machine, the combination with the turntable spindle, of a helical spring having one end fast, a pivoted lever, a chain connecting the lever with the other 20 end of the spring, a suitably mounted driving shaft, a chain wheel rotatably mounted on the shaft and carrying the chain, a ratchet and ratchet wheel for coupling the chain wheel to the shaft when rotated in one 25 direction, a countershaft adjacent the spindle, a worm and worm wheel drive between the countershaft and the spindle and a driving connection between the driving shaft and the countershaft.
- 30 4. In a talking machine, the combination with a turntable, a spring motor and a reciprocating lever for energizing the motor,

of means designed to be engaged by the lever and actuated upon such engagement to engage the turntable and stop rotary movement thereof. 35

5. In a talking machine, the combination with a turntable, a spring motor and a pivoted motor energizing lever having a forward and backward movement, of a turntable brake actuated by the lever as it approaches its rearmost point of travel. 40

6. In a talking machine, the combination with a turntable, a spring motor and a pivoted motor energizing lever having a forward and backward movement, of a pivoted 45 brake lever having one end crossing the path of travel of the former lever and the other end fitted with a brake shoe engageable with the periphery of the turntable. 50

7. The combination with a turn-table spindle, of a drive shaft geared thereto, a chain wheel on said shaft, a coil spring anchored at one end, a chain attached at one end to the free end of said spring and trained over said chain wheel, and a pivoted lever attached to the free end of said spring. 55

Signed at Winnipeg, this 8th day of October, 1919.

WILLIAM EDWARD GORDON.
